UNITED STATES PATENT OFFICE.

WALTER H. WHEELER, JR., OF STAMFORD, CONNECTICUT, ASSIGNOR TO PITNEY-BOWES POSTAGE METER COMPANY, OF STAMFORD, CONNECTICUT, A CORPORATION OF DELAWARE.

ENVELOPE-SEALING DEVICE FOR POSTAGE-METER MACHINES.

Application filed March 11, 1927. Serial No. 174,502.

This invention relates to envelope moistening and sealing devices; and is especially designed for use with small so-called postage meter machines; or like machines adapted to print postage indicia upon envelopes and other mail matter. The principal object of this invention is to save labor by utilizing the operations heretofore required for printing the indicia on mail matter by such machines to also accomplish the opening, moistening and closing of the flaps of the envelopes.

In the accompanying drawings the invention is shown as applied to a small hand operated postage meter machine, which is designed and has heretofore been used merely to print indicia on mail matter that had previously been sealed, but such machine when provided with the simple attachment of the present invention, may also perform the operations of sealing envelopes with no extra effort; because, as will be described later, the act of placing an envelope in printing position in the machine and starting it toward the printer automatically starts the operation of moistening the flap of the envelope, and the performance of the act of printing the envelope completes the moistening of the flap and closes it against the body of the envelope.

The invention, however, may be adapted to other types of machines and indicia printing machines, and I do not consider it restricted to a specific embodiment thereof illustrated in the drawings.

To enable others familiar with the art to understand and use the invention, I will explain one practical embodiment thereof as illustrated in the accompanying drawings, and refer to the claims for summaries of the essentials of the invention and novel features of construction and novel combinations of parts for which protection is desired.

In said drawings:

Figure 1 is a front elevation of a small postage meter machine, with the parts broken away to show the flap opening and moistening devices;

Fig. 2 is a side elevation of said machine partly broken away to show the flap opening and moistening devices;

Fig. 3 is a detail bottom view of the flap opener and moistener, with an envelope with its flap partly moistened;

Fig. 4 is a detail top view of the flap opener 55 and moistener.

The particular construction of the postage meter machine does not form a feature of the present invention and the postage meter machine shown in the drawings is a small portable machine a number of which are now in use. The said machine is adapted to print postage indicia upon letters, and the operating mechanisms thereof are enclosed in a casting 1. The operating mechanisms include 60 printing dies 2^a, 2^b and 2^c, mounted on a portable drum 2, which can be revolved by suitable mechanism, not shown, operated by means of a handle 3. The said dies co-operate with an impression roller 5, mounted 65 in a yieldably supported arm 4. The ends of the shaft of the impression roller 5 are yieldingly supported by springs 5^a which allow the roller to accommodate itself to envelopes having 70 uneven or wedge-shaped contents. 75

The supporting arm 4 is pivoted at 4^a and is urged upwardly by suitable spring means (not shown) to cause the impression roller 5 to press the envelopes into contact with the printing dies when the drum 2 is rotated. 80 The arm 4 also has a vertical flange 4^b on its rear side to guide the letters passing through the machine.

A feed table 6, fastened at 6^a to the base of the machine, has a vertical guide flange 85 6^b, in alignment with the guide flange 4^b of arm 4. The parts thus far referred to are parts of the aforesaid postage meter machine, as it is now sold, and are not features of the present invention.

In the operation of this machine the envelope to be printed is placed on table 6 and slid endwise by hand inward and along and over the support 4 until its forward end is under the arrow 7, marked on the housing 1. The handle 3 is then turned, and the envelope is caught between drum 2 and roller 5 and is forwarded thereby and printed by the dies 2^a, 2^b, 2^c, and discharged at the right-hand end of the machine. 95

The postage meter machine as thus constituted will only print postage indicia upon sealed envelopes. It may be taken bodily to the post office and set for a certain amount of pre-paid postage by the postal officials, and may then be removed and used to print postage indicia on mail matter until the desired amount of postage paid for is used, and then 100 105

has to be reset. The machine being small, is portable bodily and does not require a removable meter, such as is required in the larger and faster power operated types of "metered 5 mail" postage meter machines.

The object of my invention is to provide an attachment for small postage meter printing machines of the type shown—which can be readily applied to such machines, and by 10 which the envelopes may have their flaps opened, moistened and closed simultaneously with and by the operations of printing the postage indicia thereon, without requiring any additional operations, or any more work, 15 on the part of the operator than has been heretofore required in passing sealed envelopes through the machine.

As applied to the said machine the attachment is mounted on the support or arm 20 4. As shown the attachment consists of a tank or reservoir 10; a flap opener 11; a moistener 14; a guard member 12; and an adjuster member 13. These parts are preferably constructed and arranged as illustrated 25 in the said drawings when the invention is used with the particular make of postage meter machine shown in the drawings.

The tank or reservoir 10 is preferably detachably secured to the arm 4 by threaded 30 studs 10^a and knurled nuts 10^b. Said tank is preferably closed except for a slot in its top, near its outer end, through which slot the moistening wick 14 enters. This permits the machine to be tipped back, without spilling 35 water out of the tank, in order to moisten the outer end of the wick if it should become slightly dry.

The flap opener 11 is preferably made of a 40 piece of sheet metal bent upon itself in the shape of a wedge, as shown in Figs. 3 and 4, and having at its blunt end a sleeve 11^b by which it is hingedly mounted on a wire member 12^a.

A moistener 14 of wicking, felt, or other 45 suitable absorbent material, is held on the under side of the flap opener 11 by the fold 11^c; said moistener preferably extends the full length of the flap opener from the point 11^a, to the heel, and has a portion 14^a extending 50 loosely in the tank 10 which absorbs the liquid contained therein, and, through capillary attraction conveys it to the exterior part of the moistener at all points of its length.

The member 12 is preferably formed of 55 wire and has a loop or eye 12^a formed at its left-hand end, Figs. 1 and 4; and extends upward therefrom and is bent to form a horizontal portion 12^b, which extends across the tank and passes through the sleeve 11^b of the 60 flap opener 11. This portion 12^a may be detachably engaged in notches 10^c, in the sides of the tank 10; and acts as a pivot and locating point for the flap opener 11. At the right-hand side of tank 10, the wire 12 is bent 65 downward and upward in a U bend as at 12^b;

from this bend it extends inward, as at 12^c, approximately parallel to the rear edge of the opener 11, adjacent the rear edge of the moistener 14 therein. Near the free end of the flap opener 11, wire 12 is bent to the left 70 and slightly inclined downward, as at 12^d, and its extremity is inclined sharply downward, as at 12^e. The part 12^c of said wire acts as a guide for the flap of the envelopes passing under the opener 11, and presses it upward into contact with the moistener 14 by which it is moistened. The part 12^d, also 75 guides the flap, and the downward bend 12^d is for the purpose of directing the flap gently into position without shock. The U bend 12^b is designed to give resiliency to the part 12^c. The part 12^a, as has been explained, acts as a 80 pivot for the opener 11, and the eye 12^a is engaged with an adjusting member 13.

The adjusting member 13 is secured to the 85 front fold 11^c of the flap opener 11 and controls its movement. This member 13 is shown as formed of a wire and has a downwardly extending portion adjacent loop 12^a of wire, and is preferably bent as shown in Fig. 2 and has a straight threaded end portion 13^a which passes through the loop or eye 12^a of wire 12, and on this threaded portion 13^a, at opposite sides of loop 12^a, are nuts 15 90 and 15^a.

By adjusting said nuts 15, 15^a, the relative positions of the opener 11, and the guide wire 12^c can be adjusted.

The point of the flap opener 11 is yieldingly 100 pressed upward into contact with the member of the casing, as shown, by means of a spring 16 attached to eye 12^a and to a threaded rod 16^a, adjustably engaged with a thumb nut 16^b.

When the parts are properly adjusted the 105 point 11^a of flap opener 11 will be yieldingly held in contact with the under side of the housing 1, so that an envelope passed through the machine in the regular way, as above described, will have to pass between the point 11^a of the opener and the housing 1; and the point of the opener pressing against the under side of the envelope will engage the edge of the flap and open it, and enter the 110 opener and moistener between the flap and the body of the envelope. The flap passing under the opener is forced by the part 12^c of wire 12 into contact with the wick 14 and is moistened thereby.

Preferably a shield or guard 17 is secured 115 to the under side of the housing 1, above and adjacent to the opener 11, said shield being preferably made of spring metal. This shield will lightly press the forward end of the letters downward toward the impression roller and against the tendency of the opener 11, to raise them up; the shield will also protect the letter from being soiled by the ink from the printing dies.

The flap opening and moistening opera- 120 125 130

tion is started, and partially performed, by the act of placing letters in position for printing by the machine in the usual manner; and the operation of printing a letter completes 5 the operations of opening, moistening and closing the flap.

The device is so positioned as regards the printing devices that the flap of the envelope is partially opened and presented to the 10 moistener by the mere act of inserting an envelope in position for printing it. The contact of the stripping corner of the opener with the casing prevents any envelope passing between the two without having its flap 15 opened. The yieldable mounting of the flap opener enables it to readily accommodate itself to envelopes having contents of varying thickness. After the flap is moistened it passes between the printing roller and the 20 printing die which press the flap of the envelope against the body of the envelope before it is discharged from the machine.

In this machine the usual flap closer or light pressure means for closing the flap 25 against the body of the envelope after moistening and before subjecting the letter to substantial pressure by rollers is omitted; but the flap is closed against the body of the envelope by the bending of the envelope before the flap is pressed into close contact 30 therewith by the die and impression roller. This bending is accomplished by having the normal position of the moistener higher than the bite of the die and impression roller, or 35 above or out of line of the path of the letter between the printing and impression rollers, so that the body of the letter as it passes from the moistener to the rollers is curved and brought into contact with the flap before the 40 pressure is applied.

The impression roller in the machine shown is an idler and there is no mechanism acting 45 on the flap to carry it forward. Unless the flap is properly in place at the beginning of the pressure sealing its tendency to lag would increase as the letter passes between the rollers; and, but for the said bending of the letter, this would result in a false or second crease above the normal crease of the flap.

50 It will be seen that no extra work is required by the use of my invention in performing the flap opening, moistening and sealing operations in addition to the printing operation; and that the additional operations 55 have no deleterious effect on the printing operation. The very slight extra effort required to push the leading end of the letter past the point of the flap opener, (where formerly it had an unobstructed course) is 60 negligible, and in the construction shown it is performed before the printing operation begins and does not affect that operation.

The flap opening and moistening attachment 65 is readily detachable as a unit from the machine, so that if desired it can be removed

when the machine is to be taken to the post office for resetting.

I claim:

1. In combination with a postage indicia printing machine having a rotatably mounted printing die, an impression roller co-operating therewith; and a support for the impression roller; of flap opening and moistening devices mounted upon the support for the impression roller in advance of said roller 70 and closely adjacent thereto, the opener being above the bite of the die and roller, the die and impression roller co-operating during the printing operation to draw the envelope past the flap opener and moistener. 75

2. In combination with a postage indicia printing machine having a rotatably mounted printing die, an impression roller co-operating therewith; a yieldable support for the impression roller; and means for guiding an envelope to the printing die and impression roller; of flap opening and moistening devices mounted upon the support for the impression roller in advance of said roller and closely adjacent thereto, the opener being above the bite of the die and roller; the die and impression roller co-operating to draw the envelope past the flap opener and moistener and to close the moistened flap 80 during the printing operation. 90

3. In combination with a postage meter machine having a rotatable printing die, an impression roller co-operating therewith; and a movable support for the impression roller; of a flap opening and moistening attachment 100 mounted upon the support for the impression roller in advance of said roller and closely adjacent thereto; said attachment comprising a tank; a flap opener shaped and positioned to engage and open the flap of an envelope 105 moving therewith past the said opener being above the bite of the die and roller; a moistener carried by said flap opener; a member adapted to direct the flap into contact with the moistener as the envelope passes the flap opener 110 and before it is printed; the die and impression roller co-operating to draw the envelope past the flap opener and moistener during the printing operation and to close the moistened flap. 115

4. In combination with a postage indicia printing machine having a rotatably mounted printing die, an impression roller co-operating therewith; a movable support for the impression roller; and means for guiding an envelope to the printing die and impression roller; of flap opening and moistening devices mounted upon the said support in advance of said roller and closely adjacent thereto and comprising, a tank, spring means for normally yieldingly holding the flap opener in flap engaging position the said opener being above the bite of the die and roller, a moistener attached to the flap opener and extending into the tank, a guard wire adapted to 120 125 130

cause the opened flap to engage the moistener as it passes; the die and impression roller co-operating to draw the envelope past the flap opener and moistener and to close the moistened flap.

5. A moistening and flap opening attachment for postage meter machines; comprising a tank; a flap opener having a flap engaging point; a moistener carried by the flap opener 10 and extending into the tank; a wire detachably mounted on said tank and having a depending eye at one end, a portion extending parallel with the rear side of the flap opener, and another portion extending adjacent the 15 point of the flap opener, said wire being adapted to guide the opened flap into contact with the moistener; a member connected to said flap opener and having a threaded portion extending through the eye of the first 20 wire; and a spring for normally holding the flap opener, guard wire and moistener in operative position.

6. A moistening and flap opening attachment for postage meter machines; comprising 25 a tank; a wedge shaped flap opener and having a flap engaging portion at its thin end, a moistener carried by the flap opener and extending into the tank; a wire detachably mounted on said tank and having a depending eye at one end; and having a portion extending parallel with the rear side of the flap opener, and another portion extending beside the point of the flap opener; said wire being adapted to guide an open flap into contact with the moistener; a second wire connected with said flap opener and having a threaded portion extending through the eye of the first wire; adjusting members on the threaded portion of said second wire; and a 30 spring for normally holding the flap opener, moistener and guard wire in operative position.

7. A moistening and flap opening attachment for postage meter machines; comprising 45 a tank; a wedge shaped flap opener and having a flap engaging point at its thin end and a sleeve adjacent its thick end; a moistener carried by the flap opener having a portion extending into the tank; a wire detachably and pivotally mounted on said tank, and having a depending loop at one end below its pivotal portion; said pivotal portion extending through the sleeve of the flap opener, said wire having a portion extending parallel 50 with the rear side of the flap opener and another portion extending beside the point of the flap opener; said wire being adapted to guide the open flap into contact with the moistener; a second wire connected with said flap opener 55 and having a threaded portion extending through the eye of the first wire; adjusting members on the threaded portion of said second wire, and a spring connected with the first wire for normally holding the flap opener,

moistener and guard wire in operative position.

8. In a postage printing machine having a rotatable printing die, and co-operating impression roller; a flap opening and moistening device yieldably mounted immediately adjacent said impression roller and having its flap engaging portion normally above the line of contact between the impression roller and printing die whereby the body of the letter is curved as it passes from the moistener to the roller and the flap brought into contact with the body of the letter before the pressure is applied.

9. In a postage printing machine having a printing die, and co-acting impression roller; a flap opening and moistening device immediately adjacent said impression roller, said device being yieldably mounted and having its flap engaging portion normally higher than the bite of the die and impression roller 80 and in such relation to the point of bite of the die and impression roller that the body of the envelope is curved in passing between the moistener and the said point whereby the flap is brought into contact with the body 90 before pressure is applied.

10. In a postage printing machine having a rotatably mounted and driven printing die, and an undriven impression roller cooperating therewith; a flap opening and moistening device higher than the bite of the die and impression roller and immediately adjacent said impression roller, said device being yieldably mounted and having its flap engaging portion normally in such relation 100 to the point of bite of the die and impression roller that the body of the envelope is curved in passing between the moistener and the said point whereby the body of the letter is curved as it passes from the moistener to the roller 105 and the flap brought into contact with the body of the letter before the pressure is applied.

11. In combination with a postage printing machine having a rotatably mounted and driven printing die, and an undriven impression roller cooperating therewith; of a flap opening and moistening device mounted immediately adjacent said printing die and impression roller, said device being pivotally mounted and having its flap engaging point normally above the line of contact between the impression roller and printing die and a shield between the moistener and roller whereby the body of the letter is curved 110 as it passes from the moistener to the roller 115 and the flap brought into contact with the body of the letter before the pressure is applied.

In testimony that I claim the foregoing as 125 my own, I affix my signature.

WALTER H. WHEELER, JR.
